UNITED STATES PATENT OFFICE.

HENRY P. CLAUSEN, OF MOUNT VERNON, NEW YORK, ASSIGNOR TO WESTERN ELECTRIC COMPANY, INCORPORATED, OF NEW YORK, N. Y., A CORPORATION OF NEW YORK.

SELECTIVE SWITCH.

1,251,751.

Specification of Letters Patent.

Patented Jan. 1, 1918.

Application filed December 29, 1916. Serial No. 139,563.

To all whom it may concern:

Be it known that I, HENRY P. CLAUSEN, a citizen of the United States, residing at Mount Vernon, in the county of Westchester 5 and State of New York, have invented certain new and useful Improvements in Selective Switches, of which the following is a full, clear, concise, and exact description.

This invention relates to selective switches 10 and has for its object a reduction of the trunk hunting interval.

It has been found, in connection with automatic telephone systems in which the step-by-step type of selective switches is 15 used, that a subscriber sometimes succeeds in transmitting a second series of impulses before a selective switch concerned in his connection has sought out and seized an idle trunk and that, therefore, the first impulses 20 in the second train transmitted do not reach the next selective switch, with the result that a wrong connection is established.

A feature of this invention is a set of 25 brushes for each directed position of a selective switch and means for starting all in search of idle trunks immediately upon the seizure of such a switch. According to this 30 feature each set of brushes is moved forward until an idle trunk is encountered when it will be disengaged from the driving shaft and thus left in engagement with the selected idle trunk.

Another feature of this invention is the 35 means by which a line is extended through such a selective switch. A ratchet member with an auxiliary set of brushes is loosely mounted on the shaft of the selective switch, and, through an impulse directed movement, such auxiliary brushes are driven into association with the desired set of brushes of 40 such switch.

According to another feature, trunk hunting and the directed movement of such a switch are accomplished at the same time, 45 providing that a subscriber sends out a series of impulses immediately that such selective switch is seized. In some cases the hunting movement will be completed before the directive impulses are received.

50 In the drawings, Figure 1 represents diagrammatically the calling subscriber's substation connected through the line switch to a selective switch embodying this invention; and Fig. 2 is a perspective drawing of 55 a detail of the selective switch of this invention.

tion showing a set of brushes and the means for disengaging said brushes from the driven shaft when a set of terminals leading to an idle trunk is encountered.

Referring now to the drawings, let it be 60 assumed that the subscriber at substation S¹ removes his receiver from its hook and that the line is connected through a line switch (not shown), to the selector switch SS¹. A circuit is thereupon established from ground, 65 battery, right-hand winding of relay LR¹, the first position contact and side-switch wiper w¹, the telephone line and apparatus of substation S¹, the side-switch wiper w² and its first position contact, left-hand winding 70 of relay LR¹, to ground. Relay LR¹ is energized in this circuit and by attracting its armatures establishes a circuit from ground, the armature and alternate contact of relay LR¹, winding of the first slow release relay 1, to battery and ground. 75

The attraction of its armatures by relay 1 establishes a circuit from ground, the contacts 2, the right-hand armature and contact of relay 1, the contact and armature of 80 relay 3, to battery, and ground. Relay 3, through a pawl 4 and a ratchet 5 acts to rotate the shaft 6 in a direction indicated by the arrow on member 7. Relay 3 in attracting its armature breaks its own circuit in the 85 well-known manner, and through a vibrating action performs the function just described. The rotary action continues until the shaft is completely rotated, when the insulated member 8, making physical contact 90 with the contact 2, opens the circuit for magnet 3 at that point.

Loosely mounted on the shaft 1 are ten brush sets, B¹ to B¹⁰ inclusive, whose brushes b¹, b² and b³ are arranged to travel over and 95 make contact with the terminals t¹, t² and t³. In their normal positions these brushes rest upon the first set of terminals in their respective rows, and, since the busy condition of the trunks to which the terminals t¹, t² and t³ extend is indicated by ground on the test terminals t³, such grounded terminals in 100 each case provide a circuit for the energization of a magnet m¹ from ground, terminal t³, brush b³, the winding of magnet m¹, to 105 battery and thence to ground. Through the energization of the magnet m¹ the brush set will be elevated until the pin 9 fits into the recess of the collar 10, so that the rotation 110 of the shaft causes the rotation of the brushes

b^1 , b^2 and b^3 . When an idle trunk is encountered by this rotating set of brushes the energizing circuit for the magnet m^1 is broken and collar 10 is allowed to descend until the pin 9 is disengaged therefrom. Thereafter the shaft rotates but the brush set D^{10} remains in association with the detected idle trunk. Due to the resiliency of the brushes b^1 , b^2 and b^3 , the small downward movement of brush set B^{10} serves only to put a greater degree of pressure on the terminals t^1 , t^2 and t^3 , whereby the contact between such brushes and such terminals is more firmly established.

15 It may happen in this manner that several brush sets are not moved away from their initial position, while others are moved one, two, three or more steps each, and each will in time come to rest upon an idle set of 20 trunks.

When the subscriber operates his impulse transmitter D^1 , which may even occur while the hunting movement is taking place, the well-known intermittent opening of the subscriber's circuit causes the rapid vibration of the armature of line relay LR^1 . Thereupon a circuit is intermittently established from ground, armature and normal contact of relay LR^1 , left-hand armature and contact of relay 1, to a point where the circuit divides, extending in one direction through the relay 11 to battery and ground, and in another direction through the first position contact and side-switch wiper w^3 to the vertical magnet VM^1 , to battery and ground. Magnet 11, being slow to release, does not respond to the separate impulses through which it is energized, but remains energized until the train of impulses is completed.

40 Magnet VM^1 , however, does respond to the separate impulses, and through its armature and a pawl 12 elevates the ratchet member 13 carrying the auxiliary set of brushes B^{11} .

The energizing of relay 11 results in the 45 establishment of a circuit from ground, the armature and contact of relay 11, the winding of escape magnet 14, to battery and ground, whereupon relay 14 is energized. After the last impulses have been received

50 and relay LR^1 has been maintained in an energized condition for a certain period of time, relay 11 becomes deenergized, and in retracting its armatures deenergizes the relay 14, which in turn thereupon steps the 55 side-switch wipers into their second position.

After the first vertical movement of the ratchet member 13, the off-normal switch ON is closed and a ground potential from the line switch, indicated by the broken lines, 60 is projected over the conductor 15, off-normal switch ON, winding of release magnet 16, to battery and ground. Magnet 16 attracts its armature and releases the holding pawls 17 and 18 into engagement with the 65 notches of the rotary and vertical ratchets,

whereby the rotary and vertical positions attained will be retained until the release of this switch. The energization of magnet 16 also establishes a circuit from ground contact and armature of magnet 16, the second 70 position contact and side-switch wiper w^4 , through the test brush of the brush set B^{11} , to the test brush of the selected brush set, which we may assume to be in this case B^{10} , and thence over the terminal t^3 to the release 75 trunk of the next seized selective switch.

It should be noted at this point that the vertical movement of the member 13 and associated brush set B^{11} elevates the brushes b^4 , b^5 and b^6 in such a manner that they 80 come to rest upon the terminal t^4 , t^5 and t^6 of like sets leading to the brush sets B^1 to B^{10} inclusive, and in such a manner is a connection extended through the proper sets of brushes.

85 Further manipulation of the impulse transmitter D^1 will result in like movement of other selective switches until the connection is finally established. Upon the completion of a conversation, the removal of 90 the ground at the line switch in the well-known manner causes the deenergization of magnet 16, whereupon the pawls 17 and 18 are disengaged from their associated ratchet members, the member 13 is allowed to descend to its normal position, and the shaft 6 is rotated backward under the influence 95 of the spring 18. During such a backward rotary movement the pin 9 comes into a physical contact with the projection 19 of 100 the collar 10 and the brushes b^1 , b^2 and b^3 are returned to their normal position from whatever position they may have taken.

What is claimed is:

1. In a selective switch, rows of fixed circuit terminals, a set of brushes arranged to travel over and make contact with the terminals of each of said rows, means for driving said brushes over said terminals, means responsive to an electrical condition 105 denoting an idle condition for disengaging a set of brushes from said driving means, and means for selectively extending a connection through any one of said sets of brushes.

110 2. In a selective switch, rows of fixed circuit terminals, an individual set of brushes arranged to travel over and make contact with the terminals of each of said rows of terminals, a common actuating means for all of said brushes, an individual means for 115 each of said sets of brushes for disengaging said brushes from said actuating means, an auxiliary set of terminals connected to said sets of brushes, an auxiliary set of brushes arranged to travel over and make contact 120 with said auxiliary terminals, and means for selectively setting said auxiliary brushes on any set of said auxiliary terminals.

125 3. In a selective switch, rows of fixed circuit terminals, an individual set of brushes 130

arranged to travel over and make contact with the terminals of each of said rows, means common to all of said sets of brushes for actuating the same, means responsive to the idle condition of said circuit terminals individual to said sets of brushes for disengaging the same from said actuating means, and means for selectively extending a circuit through any one of said sets of brushes.

0 4. In a selective switch, rows of fixed circuit terminals, an individual set of brushes arranged to travel over and make contact with the terminals of each of said rows, actuating means common to and mechanically coupled with each of said sets of brushes, means individual to each of said sets of brushes for disengaging them from said actuating means, said disengaging means being responsive to the idle condition of said circuit terminals, an auxiliary set of fixed terminals connected to said brushes, an aux-

iliary set of brushes arranged to travel over and make contact with said auxiliary terminals, actuating means for said auxiliary brushes, and directly controlled means 25 for extending a circuit through said switch via said auxiliary brushes, said auxiliary terminals, said brushes and said terminals.

5. In a selective switch, rows of fixed circuit terminals, brushes arranged to travel 30 over and make contact with said terminals, actuating means for said brushes, means responsive to the idle condition of said terminals for setting said brushes on a set of said idle terminals in any of said rows of terminals, and means independently operable for extending a circuit through said switch in a particular row of said terminals.

In witness whereof, I hereunto subscribe my name this 28th day of December, A. D. 40 1916.

HENRY P. CLAUSEN.
